UNITED STATES PATENT OFFICE.

LUTHER L. KNOX, OF BELLEVUE, PENNSYLVANIA.

LUNCH-COUNTER STRUCTURE.

Application filed April 19, 1924. Serial No. 707,549.

My invention consists in a new and improved lunch-counter for restaurants in which are combined an eating table for patrons, a service counter for the attendants, and display means for articles of food. The most successful quick-service restaurants are located in the business sections of the communities where rents are high and space at a premium, and the object which I have in view is to provide a lunch counter with which a large number of persons may be rapidly and satisfactorily fed within a limited space.

Generally speaking, my improved lunch counter comprises a counter top whose front portion forms an eating table and its rear portion a service counter with a food display separating the same. The counter top is a relatively wide, horizontal surface of the length desired and preferably, as where the restaurant occupies a long, narrow room, of elongated U shape, having two parallel legs connected at the front end by an acute portion. The counter top may be of wood, marble, metal or opaque glass. Its support is preferably a vertical base which is set back from its outer edge sufficiently to provide clearance for the feet of patrons. Transversely disposed partitions extending from said base wall toward the rear edge of the counter top also assist in its support.

The front and rear portions of the counter top are separated by the means for displaying food. This means is preferably a vertical shield partition formed of transparent glass, and preferably from eight to twelve inches high. Said shield extends the length of the counter and divides it into portions which are preferably of about equal width, the front portion forming the eating table at which the patrons sit or stand, and the rear portion forming the service counter for the attendants.

As a modification I may elevate the food display means on legs or standards above the counter top and intermediate of its width, such means serving to divide the counter top longitudinally into an eating table and a service counter.

In the accompanying drawings, wherein I have illustrated a practical embodiment of the principles of my invention, Fig. 1 is a plan view of a U shaped lunch counter

embodying my invention and designed for use in a long, narrow room; Figs. 2, 3, 4 and 5 are enlarged sectional views taken along the dotted lines II—III; III—III, IV—IV, and V—V, respectively, and Fig. 6 is a similar section showing a modification.

The following is a detailed description of the drawings, reference being first had to Figs. 1 to 5, inclusive.

A represents the horizontal counter top which may be of any suitable material, but which is preferably opaque. The same may be elevated for patrons who stand while eating, but I prefer to make it low enough to enable patrons to sit on stools 1. The counter top A is substantially supported in place. Thus B is a base wall extending up from the floor and supporting the counter top along a longitudinal line. In case the patrons are to sit when eating the base wall B should be stepped rearwardly sufficiently to provide clearance for the lower limbs. Where the patrons are to stand said wall may be positioned nearer the front, thus providing more storage room in its rear. The counter top A is further supported by transversely disposed walls or partitions C extending rearwardly from the base wall B.

The counter top A is divided longitudinally by a vertically disposed transparent glass wall D, extending for substantially the full length of the counter. This wall D I call "the shield".

In the embodiment of my invention illustrated in the drawings, the counter top is about thirty inches from the floor and is about three feet wide and the shield is positioned at approximately the longitudinal center of the counter top and is about eight inches high. The shield D divides the counter top A into an eating table 2 for the patrons and a service counter 3 for the attendants.

Extending rearwardly from the top of the shield D is a top shelf E also of transparent glass. This top shelf, which is preferably narrow, say six inches in width, may, if desired, be used for the display of foods, but I prefer to keep it relatively clear, so that the attendants may deliver thereon foods ordered by the patrons who remove the same therefrom to the eating table. Beneath the top shelf E I provide one or more additional

transparent glass shelves F which are somewhat wider than the top shelf to facilitate placing on the shelf or shelves F foods for display, such as cuts of pie, etc. Foods 5 may also be displayed on the service counter 3 under the shelf F.

While the shield D extends for substantially the full length of the counter, the shelves E and F are interrupted at intervals 10 to provide clearance for the tea and coffee urns G and the butter portioning machines H and such other service mechanisms as it is desired to mount on the service counter.

At one or more places the service counter 15 3 is apertured or cut away, as at 4, Fig. 4, to provide access to the trays I in which chilled food, such as salads, are displayed. Such trays may be open top boxes, as shown in Fig. 4, provided with false bottoms 5 20 under which are placed the refrigerating coils 6.

In other places, as shown in Fig. 5, the service counter 3 is also cut away, as at 7, Fig. 5, for access from above to milk cans 25 J, ice cream containers or the like, which may be placed under the service counter.

The space under other portions of the service counter may be provided with shelves K, as shown in Figs. 2 and 3, and also below 30 the salad tray I in Fig. 2, or with drawers, as shown at L in Fig. 6.

It is evident that portions of the space under the service counter may be provided with sliding drawers, or cupboard doors.

35 In Fig. 6 I have shown the shield wall D' elevated above the counter top so that food may be passed under the same from the service counter 3 to the eating table 2. Thus, M represents a transparent glass plate supported from the counter top A on the legs S. The shield D' and the top and intermediate shelves E' and F' extend rearwardly from the shield D'. In this case the shelves E' 40 and D' may be of the same width as the plate M. In this modification it is preferable to elevate the plate M sufficiently so that the attendants may, while standing, look under the same and see the food before the patrons on the eating table. The plate 45 M, and the shelves E' and F' are used for the display of foods.

It is apparent that my improved lunch counter structure provides the necessary facilities for quick-service restaurants within 55 a very limited space. The usual center stands or tables for coffee urns, butter portioning machines and food displays are omitted, and the functions thereof performed by the lunch counter proper. Thus 60 a room too narrow for a lunch counter with center stands and tables, can be fitted with my invention and put into successful quick-lunch use. Not only may a substantial saving in rent be thus accomplished, but the 65 cost of fitting up the restaurant is greatly

reduced, thus lessening the overhead. Again, owing to the added convenience, less help is required to serve a given number of patrons, and the latter can be served more quickly. Moreover the interior of the restaurant presents a neater and more attractive appearance. 70

The shield, being interposed between the patrons and the food on display, prevents unauthorized handling of the food while in 75 no way interfering with the patrons' view thereof.

What I desire to claim is:—

1. A combined service counter, eating 80 table and food display structure for restaurants, comprising a wide counter having an inner service portion and an outer eating table portion of suitable width to enable patrons to eat thereat, said counter being supported at a suitable height above the serving floor to enable the attendant to serve the eating table from behind the service portion, and a transparent food protector extending intermediate the service portion and the eating table portion, said transparent 85 protector being arranged to allow the attendant to serve food to and remove dishes from the eating table portion while standing behind the service portion. 90

2. A combined service counter, eating 95 table and food display structure for restaurants, comprising a wide counter having an inner service portion and an outer eating table portion of suitable width to enable patrons to eat thereat, said counter being supported at a suitable height above the serving floor to enable the attendant to serve the eating table from behind the service portion, and a transparent food protector extending intermediate the service portion and the eating table portion, said transparent 100 protector having a horizontally extending transparent shelf and being arranged to allow the attendant to serve food to and remove dishes from the eating table portion while standing behind the service portion. 105

3. A combined service counter, eating 110 table and food display structure for restaurants, comprising a wide counter having an inner service portion and an outer eating table portion of suitable width to enable patrons to eat thereat, said counter being supported at a suitable height above the serving floor to enable the attendant to serve the eating table from behind the service portion, and a transparent food protector extending upwardly from the counter intermediate the service portion and the eating table portion and having a glass shelf extending backwardly toward the service portion. 115

4. A combined service counter, eating 120 table and food display structure for restaurants, comprising a wide counter having an inner service portion and an outer eating 125

table portion of suitable width to enable patrons to eat thereat, said counter being supported at a suitable height above the serving floor to enable the attendant to serve the eating table from behind the service portion, and a transparent food protector extending upwardly from the counter intermediate the service portion and the eating

table portion and having a glass shelf extending backwardly toward the service portion, the glass shelf being interrupted to provide space for a serving device. 10

Signed at Pittsburgh, Pa., this 16th day of April, 1924.

LUTHER L. KNOX.
